WARNING AGENT

William S. Calcott, Woodstown, N. J., assignor to
Kinetic Chemicals, Inc., Wilmington, Del., a
corporation of Delaware

No Drawing. Application July 26, 1940,
Serial No. 347,643

4 Claims. (Cl. 252—68)

This invention relates to refrigerants, which by reason of a distinctive odor, give warning of leaks in refrigerating systems.

Refrigerating systems develop leaks which cause the loss of expensive refrigerant. To give warning of leaks and to prevent loss in refrigerating systems it has been proposed to incorporate in refrigerants a substance which, by reason of its distinctive odor, will disclose a leak. However, no entirely satisfactory warning agent is yet known.

The requirements for a satisfactory warning agent are severe: It must be compatible with, and inert to, the refrigerant, the lubricants, and the metals of the refrigerating system; it must withstand the compression and expansion which occur in the system; and it must be non-toxic, non-irritating and non-pungent at the concentrations used.

It is my discovery that oenanthal, being compatible with the fluoro halogeno hydrocarbon refrigerants, and with the materials found in refrigerating systems, and being stable under the conditions of use, and lacking pungency, irritation and toxicity, is a warning agent of great value. Oenanthal is also called enanthaldehyde and is substantially n-heptaldehyde.

Refrigerants, exemplary of the class and with which it has been tried, are CCl_2F_2 , CCl_3F ,

CHClF_2 , $\text{C}_2\text{Cl}_3\text{F}_3$, and $\text{C}_2\text{Cl}_2\text{F}_4$. It produces its results at concentrations between 0.01 and 0.5%, preferably, but other concentrations are also useful. The concentration required for optimum results varies with the refrigerant. For example, 0.15% by weight of oenanthal produced optimum results with CCl_3F , and 0.1% with CHCl_2F . In each instance the refrigerants contained 10 parts of lubricating oil to 90 parts of refrigerant.

10 The oenanthal may be added to the refrigerant before or after it is charged into the unit, or it may be added to the lubricating oil.

As many apparently widely different embodiments of this invention may be made without departing from the spirit and scope thereof, it is to be understood that I do not limit myself to the specific embodiments thereof except as defined in the appended claims.

I claim:

- 20 1. A refrigerant comprising a fluorochloro hydrocarbon and a small amount of oenanthal.
2. A refrigerant comprising CCl_3F and a small amount of oenanthal.
3. A refrigerant comprising $\text{C}_2\text{Cl}_3\text{F}_3$ and a small amount of oenanthal.
- 25 4. A refrigerant comprising CCl_2F_2 and a small amount of oenanthal.

WILLIAM S. CALCOTT.
